UNITED STATES PATENT OFFICE.

CALVIN F. DUKE, OF INDIANAPOLIS, INDIANA, ASSIGNOR TO CENTRAL MACHINE WORKS, OF INDIANAPOLIS, INDIANA, A CORPORATION OF INDIANA.

TRUCK SKID.

Application filed November 8, 1922. Serial No. 599,640.

To all whom it may concern:

Be it known that I, CALVIN F. DUKE, a citizen of the United States, residing at Indianapolis, in the county of Marion and 5 State of Indiana, have invented a new and useful Truck Skid, of which the following is a specification.

In paper mills and warehouses, the large rolls of papers are usually handled or transported in a vertical position with the aid of the ordinary two-wheeled factory truck. As a result of handling in this manner considerable damage to the end of the roll is frequently caused, and it is often necessary 10 to cut off and throw away the outer edges of the paper after it is unrolled because of the unevenness of the edge which results from the injuries suffered in trucking the roll of paper in the manner above described; 15 and sometimes the injury is so great that the whole or a large part of a roll is rendered entirely unfit for its intended use. Handling paper in this way entails very little lifting, however, and consequently this 20 practice has survived in spite of the loss of paper. The finished rolls of paper come off of the paper machine in a horizontal position, and it has been recognized as desirable to keep them in this position while being 25 transported, but because no satisfactory means for handling rolls of paper in a horizontal position has been available it has been impracticable to transport the rolls in this 30 position.

35 It is the object of my invention to supply a satisfactory factory truck to make possible the handling of rolls of paper in horizontal position and of other objects, especially when of similar shape, with a minimum of 40 effort and with a minimum damage to the objects handled.

In carrying out this object I have produced a factory truck designed to carry 45 large cylindrical objects in a horizontal position; which truck is low, thus obviating the necessity of lifting the object to be handled to an excessive height; which provides a skid or incline up which the roll of paper or other similarly shaped object may be 50 rolled; and which provides a cradle for blocking the cylinder in position on the truck so that it cannot roll off.

The accompanying drawing illustrates my 55 invention: Fig. 1 is a perspective view of a truck embodying my invention, with the

skid in position to receive a roll of paper; Fig. 2 is a front elevation of the truck with the skid raised; Fig. 3 is a longitudinal section on the line 3—3 of Fig. 2; and Fig. 4 is a fragmental section substantially 60 on the line 4—4 of Fig. 2.

The truck frame proper comprises two side bars 8 and a frame-yoke 9 which forms the front cross bar of the truck. Bolts 10, 11, and 12, and tubular spacing members 13, 14, 65 and 15 surrounding them, serve to tie together and brace the side bars 8, thus making the truck frame a rigid unit. The bolt 10 acts as the axle for two rear wheels 16, which with a single front wheel 17 support 70 the truck. For steering purposes the front wheel 17 may swing on a vertical axis. This wheel 17 is carried on a spindle 18 which in turn is carried in a wheel-yoke 19. The wheel-yoke 19 is provided with a shank 75 20 extending through a central vertical hole in the frame-yoke 9. On the upper end of this shank is a split-collar 22 which is clamped on the yoke-shank by a bolt 23 as shown. On the front side of this collar 80 there are provided two ears 24 between which a handle-socket 25 is pivoted on a bolt 26. A handle 27 is secured in the handle socket 25, as by a set screw 28. The handle socket 25 is provided with two ears or stops 85 29 and 30, which serve the purpose respectively of limiting the downward and upward movement of the handle 27.

The truck skid is formed of two longitudinal members 31 spaced apart by cross 90 braces 32 and 33. The longitudinal members 31 are similarly shaped pieces of angle iron, each bent in reverse directions at two points as shown in the Figs. 1 and 3. Substantially at the foremost bend the skid is 95 pivoted to the truck frame and between the side bars 8 on a transverse axis, as by being provided with holes through which the tubular spacing member 14 is fixed. The bolt 11 is fixed vertically in such a position 100 that the top surfaces of the angles 31 are a measurable distance below the top surfaces of the side members 8. When the truck skid is in the lowered position (full lines Fig. 3) the longitudinal skid members extend rearward from the bolt 11 at a slight 105 upward angle so that at the rear end of the truck frame their top surfaces are at least as high as and preferably a slight distance 110 above the top surfaces of the truck frame

side members 8. The truck skid is shaped in this manner at this point to insure that under a heavy load the truck skid will not bend and allow the ends of the truck frame 5 side bars 8 to project into the path of the object being rolled up the skid. From this point the side bars 31 extend rearward and downward to provide an incline up which the object to be transported may be rolled.

10 The rear end of each side bar 31 is bevelled as shown in the drawings, to permit the upper surface thereof to come down to the ground or floor. From the bolt 11 the truck skid extends forward and upward to form 15 an incline, which as shown is somewhat greater than that of the rear end of the skid. I have found it to be advantageous to so proportion the truck skid that its center of gravity is in rear of its axis of pivotal 20 attachment to the frame.

On the tubular spacer 15 is pivoted the latch 36. On the rear side of this latch, teeth 37 and a stop 38 are provided. A bent rod 39 passes through a vertical hole in the 25 latch 36 and is secured therein by a set-screw 40. The front end of this bent rod is provided with a pedal 41 secured to the rod by a set-screw 42. A spring 43 acting between the latch 36 and the frame yoke 9 tends to 30 swing the latch rearwardly about the tubular spacer 15. Such rearward swinging is stopped when the bent rod 39 strikes the lower side of the frame yoke 9.

The operation of my invention is almost 35 self-evident. The skid is shown in Fig. 1 and in the full lines in Fig. 3 in position to receive the roll of paper or similar object. The object to be transported is rolled up the inclined plane formed by the rear part of the 40 truck skid and onto the truck frame proper. Continued forward movement of the object causes it to strike the front part of the truck skid, thus raising the skid to the position shown in dotted lines in Fig. 3. This movement is limited by the stop 38 on the latch 45 36. The spring 43 acts to engage the latch 36 with the front edge of the cross angle 33. As the dotted lines in Fig. 3 show, when the skid is in its raised position the intermediate 50 part between the bends of the two members 31 forms blocking which effectively prevents the cylindrical object on the truck from rolling off. When it is desired to unload the truck, it is only necessary to depress the pedal 41. This disengages the 55 latch 36 from the truck-skid cross-angle 33 and allows the rear end of the truck skid to drop to the floor because of the fact that the center of gravity of the truck skid is considerably in rear of the bolt 11. The object 60 may then be easily rolled down the skid onto the floor.

I claim as my invention:

1. In combination, a load-carrying truck 65 frame, a floor-engaging skid pivotally

mounted on said frame for facilitating the rolling of articles onto said frame, and a supporting wheel for said truck frame on each side of the axis of pivotal mounting of said skid.

2. In combination with a truck, a floor-engaging skid pivotally mounted on said truck for facilitating the rolling of articles onto the truck, and a latch pivotally mounted on said truck and operated automatically upon the raising of said skid to engage said skid and secure it releasably in raised position.

3. In combination with a truck, a cradle member pivotally mounted on said truck, 80 said member having two arms out of line with each other with the pivotal mounting of said member on said truck at the junction of said two arms.

4. In combination with a truck, a cradle 85 member pivotally mounted on said truck, said member having two arms out of line with each other with the pivotal mounting of said member on said truck at the junction of said two arms, and means for releasably securing said cradle member in fixed position relative to said truck.

5. In combination with a truck, a cradle member pivotally mounted on said truck, 95 said member having two arms out of line with each other with the pivotal mounting of said member on said truck at the junction of said two arms, one of said arms being adapted to form a skid.

6. In combination with a truck, a member 100 pivotally mounted thereon, said member extending on both sides of the axis of pivotal mounting, the part extending on one side forming a skid, and that on the other being arranged to extend from a point below the load-carrying surface of said truck to a point above such surface so that when it is depressed the skid-part of said member will be raised, and means to secure said member in position with the skid-part raised.

7. In combination with a truck, a member 115 pivotally mounted thereon, said member extending on both sides of the axis of pivotal mounting, the part extending on one side forming a skid, and that on the other being arranged to extend from a point below the load-carrying surface of said truck to a point above such surface so that when it is depressed the skid-part of said member will be raised, the skid-forming portion of said member due to its weight having a greater moment about the axis of pivotal mounting than the other portion of said member, and means to secure said member in position with the skid-part raised.

8. In combination with a truck, a member 120 pivotally mounted thereon, said member extending on both sides of the axis of pivotal mounting, the part extending on one side forming a skid, and that on the other being

- arranged to project upward above the truck when the skid-part is depressed so that when it is depressed the skid-part of said member will be raised, said truck being arranged to 45
5 carry the weight of articles upon it independently of said second extension.
9. In combination, a truck, and a combined cradle and skid member pivotally mounted thereon, said member having two 50
10 arms out of line with each other with their pivotal mounting on the truck at their junction, and one of said arms projecting beyond the truck and being bent so that its outer end may serve as a skid.
- 15 10. In combination with a truck, a member pivotally mounted thereon, said member being oppositely bent at two places on lines substantially parallel to the axis of pivotal mounting, that part of said member between the bends forming with one of the end parts a cradle, and the other end part being arranged to form a skid.
11. In combination with a truck, a member pivotally mounted thereon, said member being oppositely bent at two places on lines substantially parallel to the axis of pivotal mounting, that part of said member between the bends forming with one of the end parts a cradle, and the other end part being arranged to form a skid, the pivotal axis being at the bend between the two cradle-forming parts.
12. In combination with a truck, a member pivotally mounted thereon, one end of said member when in lowered position resting on the floor in rear of said truck, the top surface of said member extending forward and upward from the floor to a point a slight distance above the rear end of said truck, extending from this point forward and downward to a point above the pivotal 65
20 25 30 35 40
- mounting but below the top surface of said truck, and extending forward and upward from this latter point above the top surface of said truck.
13. In combination with a truck, a member pivotally mounted thereon, said member being oppositely bent at two places on lines substantially parallel to the axis of pivotal mounting, that part of said member between the bends forming with one of the end parts a cradle, and the other end part being arranged to form a skid, said member being so proportioned that its center of gravity lies between the pivotal axis and the end of the skid-part.
14. In combination with a truck, a member pivotally mounted thereon, said member extending on both sides of the axis of pivotal mounting, the part extending on one side forming a skid, and means for releasably securing said member in position with the skid-part raised, said member being so arranged that when said skid-part is raised said member extends above the load-carrying surface of the truck on each side of the axis of pivotal mounting.
15. In combination with a truck, a member pivotally mounted thereon, said member extending on both sides of the axis of pivotal mounting, the part extending on one side forming a skid, and means for releasably securing said member in position with the skid-part raised, said member being so arranged that when said skid part is raised it extends above the load-carrying surface of the truck.

In witness whereof, I have hereunto set my hand at Indianapolis, Indiana, this 3d day of November, A. D. one thousand nine hundred and twenty two.

CALVIN F. DUKE.
